LOUIS SELLIER, OF PARIS, FRANCE.

COMPOUND METAL-WORKING IMPLEMENT.

1,113,254.

Specification of Letters Patent.

Patented Oct. 13, 1914.

Application filed November 27, 1911. Serial No. 662,705.

To all whom it may concern:

Be it known that I, LOUIS SELLIER, a citizen of the Republic of France, and resident of Paris, France, have invented new and useful Improvements in Compound Metal-Working Implements, which improvements are fully set forth in the following specification.

The present invention has reference to compound metal-working implements, and it proposes an improved apparatus of the general character indicated, wherein are combined an anvil, a forge and means for supplying a forced blast of air thereto, and various devices for use in adjusting and actuating the several parts specified and for holding and operating upon the work. It further proposes the construction of certain of the parts and devices afore-mentioned, 20 and their adjuncts, in such a manner as to permit their ready attachment to and detachment from the frame or body of the apparatus, according to the use to which the latter is to be put, and to the particular 25 character of the work.

An embodiment of the invention is illustrated in the accompanying drawing wherein:

Figure 1 is a side elevation of the 30 proved implement complete; Fig. 2 is a detail view of one of the operating cranks; Fig. 3 is a detail view of one of the shafts with which said crank is adapted to be used; Fig. 4 is a detail view partly in dotted lines, 35 of the mandrel which the aforesaid shaft serves to operate; Fig. 5 is a longitudinal vertical sectional view of the implement complete; Fig. 6 is an end elevation of the anvil; Fig. 7 is a detail view of a grind- 40 stone which may be mounted upon the shaft shown in Fig. 4 in place of the mandrel; and Fig. 8 is a transverse vertical section taken on the line X—Y of Fig. 5, showing the anvil in place.

The implement represented in said drawing consists primarily of two main parts or elements, viz: A hollow fixed frame or body A which is adapted to be rigidly secured to a suitable base by means of the apertured 50 bosses w, and a movable body B. The element B has substantially the form of a hol-

low tube and is slidable endwise horizontally through alining openings in the fixed body A, its movements being effected through the agency of a feed screw K.

55

The movable body B terminates at its ends in blocks E and F, the former of which is provided with a reduced opening or duct e that constitutes the outlet from the air chamber in the interior of said body, and it is further provided with a pair of bearing openings wherein are respectively journaled the adjacent ends of the aforesaid feed screw K and the shaft Q of the helical fan or blower, the lower bearing opening having its outer portion enlarged to accommodate a fixed cross-pin V on the end of the aforesaid shaft. The screw K is provided with a washer i which abuts against the projecting upper portion of block E, and its terminal has detachably connected thereto the operating crank L by means of which it is rotated, to effect the movements of body B. The sides of said body are formed at diametrically-opposite points with longitudinal 75 seats which receive a pair of longitudinal guide rods k arranged within the interior of the fixed body A and adjustable by means of screws o as shown in Fig. 8. Said rods k serve to center body B and hold the same 80 against turning; they are adjustable in order to take up wear, and to permit their accurate positioning.

Block F, at the opposite end of body B, is formed with a series of four superposed 85 horizontal bearing openings, as depicted in Fig. 5, the lowermost opening receiving the adjacent end of shaft Q. In the two upper openings are journaled a pair of hollow shafts I and R, the former of which is represented in detail in Fig. 3. This shaft is open at both ends and is adapted to receive at its inner end the reduced conical stem p of mandrel O, (see Fig. 4), said inner end being tapered to correspond therewith, as 90 indicated by the reference character q. At its opposite end it is formed with a pair of short slots or cuts s in which fit the ends of a cross-pin r affixed to the stem u of crank G. The outer end of shaft R is also cut 95 or slotted, so that handle G can be applied to either shaft to drive the same directly.

100

Shaft I carries a gear t which meshes with a larger gear R^1 on shaft R, the latter gear meshing also, with the smaller member of a compound gear S carried by a horizontal 5 stub-shaft or pin S^1 that is journaled in the third of the bearing openings in block F. The other member of gear S is larger than the first-mentioned member, and meshes with a small gear T, fast on the fan shaft 10 Q, the arrangement being such, therefore, as to effect the rotation of the latter shaft at the requisite speed, the air being drawn into the front end of the air chamber in body B through an inlet e^2 .

15 The fixed body A carries a jaw H upon its inner end, which confronts a similar jaw H^1 provided upon block F, the portion of body A whereon jaw H is formed serving to support the anvil C, (Fig. 5), 20 which fits in a seat provided in body A and is centered and locked in place by means of a projecting lug c and a sliding bolt J. Lug c is designed to fit in a recess f , provided in the rear face of jaw H, while bolt 25 J is designed for removable engagement in a recess j in anvil C, said bolt projecting through a slot l in body A and having its stem encircled by a controlling spring g .

With the above-described anvil, there is 30 provided a forge D, (Fig. 1), which is designed for detachable connection to block E through the agency of a yoke b adapted for engagement in a retaining seat a formed on the upper end of said block. Said forge 35 is furnished with an air inlet or duct d , which, when the forge is attached to block E, registers with the duct e in the latter, so that the air forced by the fan through duct e will pass directly into and through duct d , and thence under the hearth of the forge, 40 the said duct d communicating with the hearth, as shown.

From the foregoing, it will be understood 45 that the movable body B may be adjusted relative to the fixed body A to clamp the work between the jaws H and H^1 , by rotating crank L in the proper direction, after which crank G may be applied to either of shafts I and R, and then rotated, to effect 50 the operation of the jaw; or the fan may be driven prior to the adjustment of the jaws so as to heat the work before being clamped by said jaws. Also, both or either of the soles C and D may be applied or detached, 55 according to the character of the operations to be carried out.

In addition to the instrumentalities already described, the implement embodies a tube clamp, (shown in Fig. 1), a plate P 60 for co-action with mandrel O, (Fig. 5), and a grindstone U, (Fig. 7). The first mentioned device comprises a pair of coacting jaws M and N of conventional design, whose reduced shanks are removably fitted in

65 sockets m and n , formed in the adjacent faces of the anvil jaws H^1 and H. Above the socket n , and opposite shaft I, there is formed in the face of jaw H a second socket which receives the shank of plate P. The 70 grindstone U is mounted on or affixed to a short, hollow stub-shaft V ^{1} , which is adapted to be fitted upon the rear end of the fan shaft Q, said stub-shaft being slotted or cut at its free end to receive the ends of the cross-pin V. Rotation of shaft Q, through 75 the agency of crank G, will then serve to rotate the grindstone, but it is to be understood that crank L is detached from screw K prior to the attachment of the grindstone to shaft Q. The anvil C may, if desired, be 80 provided with a hole or socket x , (Figs. 1, 5 and 6), to receive and support a removable chisel or other tool, not shown.

I claim as my invention:

1. The combination, with a work-supporting element embodying a fixed jaw-carrying body having a horizontal bore, a movable jaw-carrying body having an open-ended tubular portion slidable through said bore, and a fan mounted in said tubular portion; 85 of a forge connected to one of said bodies and communicating with the outlet end of said tubular portion; means for rotating said fan, to force a blast of air through said tubular portion into said forge; and means 90 for adjusting said movable body.

2. The combination, with an anvil and a support therefor having an open-ended air-chamber associated with it; of a forge 100 connected with said support and communicating with the outlet end of said chamber; and means for forcing a blast of air through said chamber into said forge.

3. The combination, with an anvil, a support therefor having an open-ended air-chamber associated with it, and a fan mounted in said chamber; of a forge connected 105 with said support and communicating with the outlet end of said chamber; and means for rotating said fan, to force a blast of air 110 through said chamber into said forge.

4. The combination, with an anvil, a support therefor having an open-ended air-chamber associated with it, and a fan mounted in said chamber; of a forge connected 115 with said support and communicating with the outlet end of said chamber; and driving mechanism carried by said support and connected with said fan, for rotating the latter, to force a blast of air through said chamber 120 into said forge.

5. The combination, with an anvil and a support therefor having a recessed block associated with it; of a forge provided with a yoke detachably engaged in said recess, to 125 connect said forge to said support; and means carried by said support for forcing a blast of air into said forge.

6. The combination, with a supporting element provided with a seat in its upper portion; of an anvil removably fitted in said seat, and having a recessed end; and a 5 spring-controlled bolt carried by said supporting element for engagement in said recess, to lock said anvil in place.

In testimony whereof I have signed this specification in the presence of two subscribing witnesses.

LOUIS SELLIER.
